DESIGN FOR A BUS CART OR SIMILAR ARTICLE

William E. Williams, Milwaukee, Wis.

Application April 10, 1948, Serial No. 145,639

Term of patent 14 years

(Cl. D14—3)

To all whom it may concern:

Be it known that I, William E. Williams, a citizen of the United States, residing at Milwaukee, county of Milwaukee, and State of Wisconsin, have invented a new, original, and ornamental Design for a Bus Cart or Similar Article, of which the following is a specification, reference being had to the accompanying drawing, forming part thereof.

The single figure of the drawing is a view in perspective showing a bus cart embodying my ornamental design.

I claim:

The ornamental design for a bus cart or similar article, as shown.

WILLIAM E. WILLIAMS.
